M. MORTENSEN

BARREL STAND

Filed April 4, 1923

Fig. 1

UNITED STATES PATENT OFFICE.

MARTIN MORTENSEN, OF BATTLE CREEK, IOWA.

BARREL STAND.

Application filed April 4, 1923. Serial No. 629,867.

To all whom it may concern:

Be it known that I, MARTIN MORTENSEN, a citizen of the United States, residing at Battle Creek, in the county of Ida and State 5 of Iowa, have invented new and useful Improvements in Barrel Stands, of which the following is a specification.

This invention relates to stands or supports, and an object of the invention is to 10 provide a support for barrels which is designed to facilitate the relatively easy movement of a heavy filled barrel from a vertical position into an elevated horizontal position to facilitate the removal of the contents 15 from the barrel as needed.

Other objects of the invention will appear in the following detailed description taken in connection with the accompanying drawing wherein:—

20 Fig. 1 is a side elevation of the improved stand or support showing it in horizontal barrel supporting position.

Fig. 2 is a side elevation of the support showing it in position prior to the tilting of 25 a barrel into horizontal position.

Fig. 3 is a vertical cross section through the stand taken on the line 3—3 of Fig. 1.

Referring more particularly to the drawings, the improved stand or support 30 comprises angle iron side rails 1 and 2 which extend along the sides of the stand and are connected at spaced points by transversely extending bowed barrel supporting strips 3. The rails 1 and 2 have supporting legs 4 connected thereto, the lower ends of which 35 are in turn connected by cross braces 5. Angle braces 6 are provided for bracing the legs 4 and the floor engaging cross braces 5. The side rails 1 and 2 are also braced by diagonal braces 7, 8 and 9 which are arranged 40 to provide the maximum strength to the stand and to provide breakage resisting supports at the points of the stand where the greatest stress is received. A hand lever 10 is attached to certain of the supporting legs 45

4, and it projects outwardly beyond the forward supporting legs a pre-determined distance as shown at 11 in Figs. 1 and 2 of the drawings that is it projects beyond the forward supporting legs 4 substantially the same distance which the straight portions of the side rails 1 and 2 project. The forward ends of the side rails 1 and 2 are bent transversely and beveled as shown at 12 and 13 respectively so as to permit their insertion beneath a barrel, as shown in Fig. 2 of the

drawings. The hand lever 10 projects beyond the rear end of the side rails 1 and 2 a considerable distance so as to provide a leverage over its end 11 as a fulcrum to facilitate the tilting of a barrel as shown at A from a vertical into a horizontal position.

A claw hook or gripping hook 14 is pivotally carried by one of the legs 4 and is adapted to be swung to engage over the upper end of the barrel as shown in Fig. 2 of the drawings to provide connection between the stand and the upper end of the barrel so that when the stand is tilted on the end 11 as a fulcrum the barrel A will move with the 60 stand and rest, in horizontal position upon the supporting strips 3 permitting the barrel to be tapped preferably at one end for dispensing its contents. It is understood that when the barrel is in horizontal 65 position it is supported from the supporting legs 4.

From the foregoing description taken in connection with the accompanying drawings it will be apparent that a supporting 70 stand has been provided by means of which barrels of material such as barrels of oil may be converted from vertical position or from horizontal position upon the floor ground into an elevated dispensing position with a 75 minimum amount of labor. About garages, farms and other places, barrels of oil are left upon the floor or ground by the deliverer and it has heretofore been the common practice to lift the barrels manually upon 80 supporting stands to elevate them sufficiently to permit the dispensing of their contents, such lifting requiring considerable 85 heavy and hard work which is eliminated by the use of the present stand.

It is, of course, to be understood that the invention may be constructed in other manners and the parts associated in different relations and, therefore, I do not desire to be limited in any manner except as set forth in 90 the claim hereunto appended.

Having thus described my invention what I claim is:—

A stand comprising supporting legs arranged in rectangular formation, angular 105 side rails extended longitudinally and connected to the supporting legs, one end of each said rail projecting beyond the supporting legs and bent transversely to the body portion and bevelled at its extreme 110 end, transversely extending bowed barrel supporting strips having their ends connect-

ed to the side rails, diagonal braces between the side rails and supporting legs, a hand lever extending longitudinally of the stand on an inclined plane with its ends projecting beyond both ends of the frame, angular cross braces attached to the lower ends of the supporting legs with one of its flanges ex-

tending upwardly onto the legs and rigidly connected thereto and a plurality of angle braces each having one end connected to the ¹⁰ cross braces and the other end connected to the supporting legs.

In testimony whereof I affix my signature.
MARTIN MORTENSEN.
